UNITED STATES PATENT OFFICE.

ELMER S. SHIMER, OF MILTON, PENNSYLVANIA, ASSIGNOR TO SAMUEL J. SHIMER AND SONS INCORPORATED, OF MILTON, PENNSYLVANIA.

ROTARY CUTTER-HEAD.

No. 844,197.

Specification of Letters Patent.

Patented Feb. 12, 1907.

Application filed November 24, 1906. Serial No. 344,890.

To all whom it may concern:

Be it known that I, ELMER S. SHIMER, a citizen of the United States, residing at Milton, in the county of Northumberland and State of Pennsylvania, have invented 5 certain new and useful Improvements in Rotary Cutter-Heads, of which the following is a specification.

This invention relates to that class of rotary cutter-heads for woodworking-machines which are used particularly for cutting dadoes and for cutting grooves across the fiber of the wood. For these purposes circular saws, set at any deviation from a right angle upon the shaft or mandrel, have 15 heretofore usually been employed, the same being known as "wobble-saws." Considerable difficulty has been experienced in properly setting or adjusting such saws to obtain 20 the desired results; and one object of the present invention is to provide an improved cutter-head for cutting grooves across the fiber of the wood without resorting to the use of wobble-saws. Cutter-heads of this character are usually employed in connection 25 with saw-benches having short mandrels; and a further object of the invention is to provide an improved cutter-head which may be conveniently and securely mounted for 30 operation upon such short shaft or mandrel.

A further object of the invention is to construct an expansion cutter-head which may be conveniently, quickly, and expeditiously 35 adjusted for the purpose of cutting grooves of various widths.

Further objects of the invention are to simplify and improve the construction and operation of the class of cutter-heads to 40 which the invention belongs.

With these and other ends in view, which will readily appear as the nature of the invention is better understood, the same consists in the improved construction and novel 45 arrangement and combination of parts, which will hereinafter be fully described, and particularly pointed out in the claims.

In the accompanying drawings has been 50 illustrated a simple and preferred form of the invention, it being, however, understood that no limitation is necessarily made to the precise structural details therein exhibited,

but that changes, alterations, and modifications within the scope of the invention may be resorted to when desired. 55

In the drawings, Figure 1 is a side elevation of a cutter-head constructed in accordance with the principles of the invention. Fig. 2 is a vertical sectional view of the same, taken on the plane indicated by the line 2 2, 60 Fig. 1. Fig. 3 is a vertical sectional view taken at right angles to Fig. 2. Fig. 4 is a top plan view. Fig. 5 is a perspective detail view of the lower or main section of the improved cutter-head. Fig. 6 is a perspective detail view showing the upper or adjustable section of the improved cutter-head detached. 65

Corresponding parts in the several figures are denoted by like characters of reference. 70

The improved cutter-head is composed of a lower or main section A and an upper adjustable section B. The main section A comprises a sleeve or hub 1, which is provided with diametrically opposite radially-extending flanges 2 2, each extending around approximately one-fourth the circumference of the hub or sleeve. The latter has a bore 3 of large diameter and is provided at its lower extremity with an internal annular flange 4, 75 bounding the central aperture 5, which is for the admission of the shaft or mandrel 6, upon which the cutter-head is mounted, said shaft or mandrel being provided with an annular shoulder 7, forming a seat for the cutter-head 80 and with a threaded extension 8, which extends through the aperture 5 for the reception of the nut 9, which latter may be tightened against the flange 4 of the cutter-head 85 by means of a socket-wrench which may be 90 conveniently inserted into the bore of the sleeve or hub of the cutter-head. The latter may, in this manner be very conveniently and securely, as well as expeditiously, 95 mounted in position for operation.

The hub or sleeve of the main section of the cutter-head is exteriorly screw-threaded for the greater portion of its length above the radial extending flanges 2 2 for the reception of a circular nut 10, which is provided at intervals with recesses 11 to enable said nut to be operated by means of an ordinary spanner-wrench. The adjustable member or section B of the cutter-head comprises a hub- 100

sleeve 12, which is provided at its lower end with diametrically opposite recesses or longitudinally cut-away portions 13, corresponding with diametrical flanges 2 2 of the main section A, the hub-sleeve being thus bodily bifurcated and forming a pair of diametrically opposite segmental extension-lugs 14 14, engaging the interspaces between the flanges 2 2 of the main section A, it being understood that the hub 12 of the section B is of internal diameter equal to the external diameter of the hub 1 of the section A, upon which the section B is slidable and adjustable, the hub 12 being connected for rotation with the nut 10, so that by turning said nut the section B will be axially adjusted upon and with relation to the section A. The hub 12 of the section B is provided with radially-extending quarter-section flanges 15 15, which are in registry with the extension-lugs 14, and consequently with the interspaces between the flanges 2 2, extending from the hub 1 of the section A. It will be observed that the flanges 15 extend radially from the hub-sleeve and at approximately right angles to the axis of said sleeve, while the so-called "extension-lugs" 14, which are entirely distinct from said flanges, are, properly speaking, a portion of the sleeve, and may thus without affecting the thickness or dimensions of the flanges be made of any desired length, it being evident that by increasing the length of the extension-lugs the scope or range of adjustment of the cutter-head is correspondingly increased. It is preferred that the flanges 2 2 and 15 15 be slightly in excess of ninety degrees, so that said flanges will slightly overlap, as will be clearly seen by references to Fig. 4 of the drawings.

The flanges 2 2 and 15 15 of the members or sections of the cutter-head support the cutter-tools, which consists of saw-knives 16 and circular bits 17, each flange supporting a saw-knife and a bit, and said saw-knives and bits being disposed in alternate order upon the opposing sides or faces of the flanges 2 2 15 15, the saw-knives being in advance of the circular bits. By this arrangement the saw-knives will cut the square edge of the groove across the fiber of the wood, and the circular bits or cutters will remove the material between the edges of the groove, thus clearing out the entire width of the groove. It will readily be seen that the width of the groove to be cut may be controlled by the proper adjustment of the section or member B of the cutter-head, which is effected by simply turning the nut 10. By so adjusting the section B as to place the circular cutters in line with one another a groove may be cut of a width corresponding with the width of a single circular bit or cutter. By expanding the cutter-head the width of the groove may

be increased until it approximates the combined width of two of the circular bits, it being necessary for the best results that the circular bits should be slightly overlapped when the device is in operation. Wider circular bits may be substituted for the comparatively narrow ones shown in the drawings, the capacity of the cutter-head for cutting grooves of various widths being limited only by the length of the extension-lugs 14, which by engaging between the flanges 2 2 of the hub 1 serve to keep the sections A B of the cutter-head interlocked for operation.

From the foregoing description, taken in connection with the drawings hereto annexed, the operation and advantages of this invention will be readily understood by those skilled in the art to which it appertains. It is not deemed necessary to show in detail how the depth of the groove cut may be gaged, this being no part of the present invention. The general construction of the device is simple, the desired adjustments may be easily effected, and the improved device has been found in actual operation to be thoroughly efficient for the purposes for which it is intended.

I claim—

1. In an expansion cutter-head, a main hub having radially-extending tool-carrying flanges, and an adjustable hub-sleeve slidable upon the main hub having radially-extending tool-carrying flanges, said hub-sleeve being bodily bifurcated to form extension-lugs engaging the interspaces between the tool-carrying flanges of the main hub, projecting longitudinally of the head beyond the tool-carrying flanges.

2. In an expansion cutter-head, a main hub having diametrically opposite radially-extending tool-carrying flanges, an auxiliary hub-sleeve slidable upon the main hub and having a longitudinal bifurcation forming segmental extension-lugs that engage the interspaces between the tool-carrying flanges of the main hub, said auxiliary hub being provided with radially-extending tool-carrying flanges projecting radially beyond the extension-lugs and registering with the interspaces between the tool-carrying flanges of the main hub, and means for effecting adjustment of the auxiliary hub upon the main hub.

3. In a cutter-head of the class described, a main hub having a bore of large diameter and provided with an internal annular flange at its lower end, said hub being externally screw-threaded at its upper end and provided with radially-extending tool-carrying flanges below its threaded portion, in combination with an adjustable hub-sleeve slidable upon the threaded portion of the main hub, said adjustable hub-sleeve having a longitudinal bifurcation forming segmental exten-

sion-lugs engaging the interspaces between the tool-carrying lugs of the main hub and diametrically-extending tool-carrying flanges on the main body of the hub-sleeve and a nut 5 engaging the threaded portion of the main hub and connected for rotation with the adjustable hub.

In testimony whereof I affix my signature in presence of two witnesses.

ELMER S. SHIMER.
